UNITED STATES PATENT OFFICE.

MAX A. MINTZ, OF CLEVELAND, OHIO, ASSIGNOR TO THE FANNER MANUFACTURING COMPANY, OF CLEVELAND, OHIO, A CORPORATION OF OHIO.

AWNNG-OPERATING MECHANISM.

Application filed September 13, 1923. Serial No. 662,461.

This invention relates to an awning operating mechanism. More particularly, it comprises a gear box having an automatic locking device.

5 Gear boxes for awning operating mechanism have been heretofore provided with locks of various types, but in many instances, numerous and relatively heavy parts have been employed for locking purposes and said 10 parts have not been disposed in such relation to each other as to be readily accessible for adjustment and repair. Such devices have not infrequently included a locking device subject to a large amount of wear and 15 requiring specially formed means for operating the same.

The object of the present invention is to simplify the construction of automatically locked gear boxes of this type. Another object 20 is to provide a locking device having four different locking positions for each revolution of the gear wheels in order that an awning may be locked in substantially its full raised position. A further object is 25 to provide a locking plunger within the hub portion of one of the beveled gear wheels adapted to be unlocked by means of a rounded nose on the end of the crank pin. Other objects will appear in the course of 30 the following description. To the accomplishment of the foregoing and related ends, said invention, then, consists of the means hereinafter fully described and particularly 35 pointed out in the claims.

35 The annexed drawing and the following description set forth in detail certain mechanism embodying the invention, such disclosed means constituting, however, but one of various mechanical forms in which the 40 principle of the invention may be used.

In said annexed drawing:

Figure 1 is a front elevation of the awning operating mechanism comprising the invention;

45 Figure 2 is a side elevation thereof;

Figure 3 is a front elevation of the apparatus with the cover section removed;

50 Figure 4 is a central vertical section taken along the line 4-4 shown in Figure 1 looking in the direction of the arrows;

Figure 5 is a sectional detailed view taken

along the line 5-5 shown in Figure 4 looking in the direction of the arrows;

Figure 6 is a sectional detailed view taken 55 along the line 6-6, shown in Figure 4 looking in the direction of the arrows;

Figure 7 is a front elevation of the supporting spider;

Figure 8 is an end elevation of the supporting spider;

Figure 9 is a side elevation on a greatly 60 reduced scale of the crank utilized for operating the apparatus.

The device illustrated in the drawings 65 comprises a casing, 1, having a flanged lower portion, 2, with extensions, 3, at its upper and lower edges for securing the same to the front of a building, and a cover portion 4. Said cover is provided centrally at its outer side with a bearing, 5, for the hub 70 extension, 6, of the beveled gear, 7, adapted to be housed immediately within said cover section. The meeting edges of the cover and base portion of the housing are provided with a bearing, 8, for the hub extension, 9, of a second beveled gear, 11. Said 75 last mentioned hub extension is provided with a squared shank, 12, adapted to engage the sleeve, 13, of a driving shaft of the awning apparatus. Within said hub extension 80 and said squared shank an internal chamber or housing, 14, for a locking plunger, 15, is provided. Said housing includes a squared opening, 16, through which said plunger is 85 adapted to reciprocate. Within the upper end of said housing a spring receiving chamber, 17, is provided, said spring, 10, abutting the upper end of said chamber which is provided centrally with a circular aperture, 18, to receive the small extension end, 19, of 90 said plunger. Immediately beneath said extension end the plunger is provided with a squared locking section, 21, and adjacent thereto with a cylindrical section, 22, terminating in an enlarged flange, 23, which 95 limits the reciprocation of the plunger in each direction. Immediately beneath the enlarged flange the plunger is provided with a squared body portion, 24, having a beveled point, 25.

100 The meeting edges of the bottom portion of the housing and the cover section thereof

are notched centrally of the two opposite side portions and at the lower central margins thereof to provide seats, 26, for holding a supporting spider, 27. Said spider is adapted to be positioned centrally of said casing and is provided with three legs having extension lugs, 28, adapted to engage said sides and notches.

Said spider is provided with a pair of 10 journals, 31, 32, mounted at right angles to each other, one of said journals being adapted to receive a hub extension formed upon the first of said beveled gears above described and the other of said journals providing an extension flange, 33, over which the second of said gears, above described, is adapted to have rotatable engagement when said beveled gears are positioned in operative relation to each other. Immediately 15 adjacent to the last journal there is provided a squared aperture, 34, in said spider.

Said aperture is adapted to receive the squared main body section, 24, of the plunger. The circular flange, 23, upon the 20 plunger is adapted to bear against the bottom of a counter-bored portion, 35, of said spider within the extension flange of said journal, when the plunger is in its uppermost position, at which time the squared 25 locking section of the plunger will be held in the same plane as the squared portion of the housing within the hub extension of the first mentioned beveled gear. Thus, the two squared portions of the plunger 30 will serve to key all of said parts together and hold the same against rotation.

The second beveled gear is provided with a hollow hub section, 36, of square cross-section at its outer end, 37, to receive the 35 squared section, 41, of a crank, 42, for operating the device. The inner portion, 43, of said hollow hub is of smaller diameter than the outer portion and is adapted to receive a pin extension, 44, upon the crank 40 arm, said pin extension having a beveled end 45, to engage the lower end of said plunger and force the same upwardly against the pressure of its coiled spring. When so elevated the locking section of the 45 plunger is moved upwardly out of alignment with the squared portion of the chamber within the first mentioned beveled gear wheel into an enlarged recess which thus permits the free turning of said beveled gear and its associated mechanism.

It will be noted that by utilizing a plunger, having a squared locking section, there are four positions in which the gears may be locked during a single rotation of 60 the parts, and thus when an awning is raised it may be locked in fully elevated position.

The lower section of the casing is provided with enlargements, 51, at opposite corners of its upper side and centrally of its

lower side and said cover is provided with projecting lugs, 52, at points in registry with said enlargements, said lugs being apertured and enlargements being screw-threaded to receive locking screws 53 to hold the 70 parts in engagement. The enlargement and lug on the lower side are each cut away on their adjacent faces to provide seats 54 and 55, respectively, to receive a projecting ear 75 56 on the lower extension of the spider which is apertured to permit the passage of the holding screw therethrough. Thus said lower screw serves to hold the two sections of the casing in engagement and at the same time to engage and firmly hold the spider 80 in position.

The operation of the device has already been indicated, but it should be pointed out that the mechanism of the gear box is of simple and durable construction and that 85 all the parts are readily accessible and separable from each other upon unfastening the cover from the bottom section. No specially shaped parts are required to unlock the device, the pin extension of the crank arm 90 being a beveled end cylindrical pin not in any way subject to injury through careless handling.

At the base of the casing adjacent the central enlargement and its companion lug 95 there are provided two drain holes 57, which prevent the accumulation of water within the casing. A closure plate (not shown) of thin sheet metal may be applied to the rearward face of the casing when the same is 100 not applied to a wooden structure which in itself serves as an adequate closure.

Other modes of applying the principle of my invention may be employed instead of the one explained, change being made as 105 regards the mechanism herein disclosed, provided the means stated by the following claims or the equivalent of such stated means be employed.

I therefore particularly point out and distinctly claim as my invention:—

1. An awning raising mechanism comprising a drive gear with an opening therethrough and a driven gear, said driven gear provided with a shank having an opening therethrough, the opening adjacent the gear end being squared, a detent within said opening provided with a squared portion adapted to engage with said squared opening in the driven gear, resilient means within the opening for holding said detent in locked position, and a crank adapted to engage the drive gear provided with means for raising said detent to unlock said driven gear.

2. An awning raising mechanism comprising a drive gear with an opening therethrough and a driven gear, said driven gear provided with a shank having an opening therethrough, the opening adjacent the gear end being squared, a detent within said

opening provided with a squared portion adapted to engage with said squared opening in the driven gear, a further member on said detent adapted to be so engaged as to maintain the squared portion within said squared opening, resilient means within the opening for holding said detent in locked

position, and a crank adapted to engage the drive gear provided with means for raising said detent to unlock said driven gear.

10

Signed by me this 8th day of September 1923.

MAX A. MINTZ.
